UNITED STATES PATENT OFFICE

2,631,578

TOY PISTOL

William F. Laughlin, St. Charles, Ill.

Application April 13, 1948, Serial No. 20,773

1 Claim. (Cl. 124—27)

1

This invention relates to improvements in semi-automatic toy pistols.

An object of the invention is to provide an improved semi-automatic toy pistol which will be provided with a magazine for holding a number of balls or pellets which will be shot from the pistol when the trigger of the pistol is actuated.

Another object of the invention is to provide an improved semi-automatic toy pistol having a magazine for holding a number of balls or pellets and a spring projected plunger which may be manually cocked prior to the actuation of the pistol trigger for releasing the plunger to forcibly propel a ball or pellet from the pistol.

A further object of the invention is to provide an improved semi-automatic toy pistol which will be quite accurate in use, and relatively inexpensive to manufacture and produce.

Other objects will appear as the description proceeds.

In the accompanying drawings which form a part of this application,

Figure 1 is a longitudinal sectional view through the improved semi-automatic toy pistol;

Figure 2 is a front elevational view of the improved semi-automatic toy pistol;

Figure 3 is a top plan view of the improved semi-automatic toy pistol with a part thereof being broken away and in section to show the loading opening into the pistol magazine; and

Figure 4 is a sectional view taken on the line 4—4 of Figure 1.

Like characters of reference are used throughout the following specification and the accompanying drawings to designate corresponding parts.

The semi-automatic toy pistol is generally designated by the reference numeral 1, and is formed by two substantially similar halves 2 and 3 with the line of juncture extending longitudinally and vertically through the pistol 1.

Securing screws 4 and 5 are adapted to extend through the cooperating halves 2 and 3 of the pistol 1 for holding the same in assembled position.

A rear sight 6 and front sight 7 are supported upon the upper edge of the pistol barrel 8, being preferably formed integrally therewith.

The barrel 8 is hollowed out as at 9 and is formed with oppositely disposed longitudinally extending slots 10 and 11 through its side walls, and the forward end of the hollowed out portion 9 of the barrel 8 is slightly restricted to form an annular internal shoulder 12. The bore of the barrel thus is of two diameters. The advance end zone within which the missile has its movement is calibrated to missile dimensions, while the bore in the rear thereof, in the rear of shoulder 12, is of larger diameter and of extended length, and is formed with the slots 10 and 11 on its opposite sides.

A plunger or missile-projecting element 13 having a rubber cap 14 attached to its forward end is

2

slidably disposed in the hollowed out bore 9 of the barrel 8, and said plunger 13 is further provided with the integral oppositely disposed cocking grips 15 and 16 which extend laterally through the slots 10 and 11 in the barrel 8. The rear end of the plunger 13 is reduced at 17 to support the forward end of a strong coil power spring 18 disposed in the rear of the bore 9 of the barrel 8, and an annular groove or seat 19 is formed about the plunger 13 for engagement by the hooked trigger catch 20 on the end of the trigger 21. The trigger 21 is pivotally supported upon the cross pin 22 and has its finger engaging end 23 disposed within the usual trigger guard 24 formed integrally with the pistol 1. A small coiled trigger spring 25 is set in the pistol for engagement with the pin 26 on the trigger 21 for normally holding the same under resilient tension.

A magazine bore 27 is formed longitudinally of the pistol barrel 8 in parallel relation below the bore 9, and has its forward end curved upwardly to connect with the forward end of said bore 9.

A loading plunger 28 is slidably disposed in the magazine bore 27 and is formed with a laterally extending loading grip 29 which is slidably disposed in the longitudinal slot 30 formed through the barrel portion 8 of the pistol 1.

The rear end of the loading plunger 28 is reduced at 31 and supports a coil loading spring 32 which is disposed in the rear of the magazine bore 27.

A rounded or concave seat 33 is formed in the front end of the loading plunger 28 for engagement with the balls or pellets 34 which are fed into the magazine bore 27 through the side loading opening 35. A cross rivet 36 is disposed adjacent the front of the barrel 8 for holding the sections or halves 2 and 3 firmly assembled.

A stock or grip portion 37 for the pistol 1 will be formed integrally with the barrel portion 8, and the pistol will resemble an automatic type of pistol.

In operation, the balls or pellets 34 will be fed through the side loading opening 35 into the magazine bore 27 after the loading plunger 28 has been pulled back as far as possible, until no more balls or pellets 34 will go into the magazine bore 27. To shoot the pistol, the cocking grips 15 and 16 are pulled back until the trigger catch 20 is seated in the annular seat 19 in the plunger 13. Thereafter it is only necessary to pull the finger portion 23 of the trigger 21 and the plunger 13 will be forcibly projected by the spring 18 to project the ball or pellet 34 from the pistol. The same procedure will be followed every time the pistol is to be fired. All of the balls or pellets 34 except the last two may be projected by the pistol before it has to be reloaded.

From an inspection of Figure 1, it will be observed that the outer or foremost two end balls 34a and 34b are aligned transversely of the pistol body, with the end ball 34b alone positioned in

the bore 9 of the barrel 8 at the extreme outer end thereof. Attention is also called to the fact that the magazine 27 holding the charge of ammunition or balls communicates with the bore 9 of the barrel 8 at the outer end of the bore. With an arrangement of this character, the end ball 34b is fired by impact when contacted by the rubber end 14 of the firing plunger 13. By positioning the ball 34b to be fired at the extreme outer end of the barrel bore, friction between the ball and barrel is practically eliminated, so that the ball travels a shorter distance within the pistol without friction and has increased power imparted thereto by the impact engagement therewith of the firing plunger.

The assemblage thus described presents a number of characteristic features, some of which have been referred to, others of which will now be indicated. Among these is the relative lengths of the calibered missile-discharging portion of the bore and the larger diameter portion in the rear of shoulder 12. As above pointed out, the length of the former is comparatively short, and is calibered for the missile which is assumed to be used with the pistol. As shown, however, the length of the bore in the rear of such advance calibered zone is comparatively long, a number of times the length of such advance zone, the rear end of the bore being located as extending on a plane materially rearward of a plane extending on the rear face of bore 27. This portion of bore 9 contains the spring 18 and the plunger 13 which forms the missile-projecting element of the assemblage, and the length of this portion of the bore, in connection with the length of the element, presents one of these characteristic features, as will be understood from the following.

Plunger or element 13 is short in comparison with the length of this portion of the bore. As indicated in Fig. 1, which shows the element in cocked position, a plane which extends on the forward face of cap 14, extends through the follower 28 when the magazine is completely loaded, so that the element 13, as well as spring 18, are located rearward of such plane. As shown in said figure, the distance between such plane and the positioned missile 34b is more than three times the length of the calibered zone of the bore. Obviously, the element 13 must travel this distance in order to reach the positioned missile and through the power provided by spring 18, and must make its contact with sufficient power as to produce the desired projection of the missile, the latter being provided by the impact of cap 14 with the positioned missile.

This result is obtained because of certain conditions produced because of such length. For instance, this distance length also represents the distance which the spring 18 can expand when its tension is released through trigger release. Hence, spring 18 may be made with many convolutions and thus be capable of expanding even greater distances without liability of overstressing or damage. Actually, the spring 18 in the present invention is not fully expanded at the time of impact, although material expansion is had in covering the distance. Such expansion, however, is more in the nature of a developing cycle, it being understood, of course, that in the cocked position of element 13 the spring 18 is under maximum contraction.

The short length of element 13 makes it of comparatively light weight, but the fact that it is under restraint of the trigger compels the spring initially to overcome the inertia of the

element when the trigger is released, thus beginning the element advance; afterward the element is in motion. While the tensile power of the spring decreases as it expands, the decrease is at such rate that the speed of advance of element 13 is being accelerated, reaching its peak during the latter part of the advance, at which time its momentum is an active factor in producing the speed and tends to maintain the accelerated speed, with the result that the impact is produced under the accelerated speed conditions. In other words, the impact value is produced through the combined action of the expanding spring and the momentum factor developed by such expansion and in the presence of the decreasing power value of the spring as it expands, the developing acceleration producing the momentum values.

It will also be understood that the plunger cap 14 may be made of any suitable substance harder than rubber and may form an integral part of the plunger. Also, the shot or balls 34 may be made of any suitable material of a resilient character in the event that softer ammunition or shot is desired.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention, what I claim as new and desire to secure by Letters Patent of the United States is:

In a semi-automatic toy pistol, a barrel having a projector bore formed therein, a spring projected plunger slidably in said bore, a magazine bore formed beneath and parallel to said projector bore, and a trigger release for said plunger comprising a U-shaped member pivotally mounted at the inner end of said magazine bore, the upper leg of said U-shaped member extending inwardly a substantial distance between said projector and magazine bores and having a hook element projecting into the upper bore selectively engageable with said plunger, the lower leg of said U-shaped member extending inwardly beneath and normally substantially parallel to said magazine bore, a downwardly inclined finger projection at the end of said lower leg, and spring means engaging said trigger release to normally hold said hook element in engagement with said plunger.

WILLIAM F. LAUGHLIN.
